UNITED STATES PATENT OFFICE.

ORANGE O. OZIAS, OF DAYTON, OHIO, ASSIGNOR TO THE COMPUTING SCALE COMPANY, OF OHIO.

DESIGN FOR A SCALE-FRAME.

SPECIFICATION forming part of Design No. 32,007, dated December 19, 1899.

Application filed October 30, 1899. Serial No. 735,326. Term of patent 7 years.

To all whom it may concern:

Be it known that I, ORANGE O. OZIAS, of Dayton, in the county of Montgomery and State of Ohio, have produced a new and original Design for a Scale-Frame, of which the following is a specification, reference being had to the accompanying drawing, forming part thereof, in which like letters refer to like parts.

The figure in the drawing illustrates a perspective view of a scale-frame embodying my invention and design.

The essential feature of my invention consists of a base having two columns rising from near one end thereof and surmounted by a cylinder and two projections rising from near the opposite end of said base.

In said drawing, 10 represents said base,

11 and 12 represent said columns rising from near one end of said base, 14 represents said cylinder surmounting said columns, and 15 and 16 represent said projections rising from near the opposite end of said base. 17 represents an opening through the top of said base between said projections 15 and 16 and the columns 11 and 12. 25

What I claim is—

The design for a scale-frame, substantially as shown and described.

In witness whereof I have hereunto set my hand this 10th day of October, 1899.

ORANGE O. OZIAS.
